UNITED STATES PATENT OFFICE.

RICHARD J. NETZEL, OF CLEVELAND, OHIO.

PAPER-FEEDING MACHINE.

1,305,399.

Specification of Letters Patent. Patented June 3, 1919.

Application filed January 16, 1917. Serial No. 142,600.

To all whom it may concern:

Be it known that I, RICHARD J. NETZEL, a citizen of the United States, residing at Cleveland, in the county of Cuyahoga and 5 State of Ohio, have invented certain new and useful Improvements in Paper-Feeding Machines, of which the following is a specification.

My invention relates to improvements in 10 paper feeding machines, and more particularly to that class or type known as "pile feeders" used in connection with the feeding or delivery of sheets of paper to printing presses from a stack or pile of paper.

15 The primary object of my invention is the provision of a generally improved machine of this class which will be exceedingly simple in construction, cheap of manufacture, and efficient in use.

20 A further object of the invention is the provision of a machine of this class which may be readily attached or used in connection with printing presses of varying forms, or types, as well as one which may be readily 25 adjusted for the feeding or delivery of sheets of varying forms and dimensions.

A still further object is the provision of 30 improved pile supporting and sheet feeding and sheet separating mechanism together with improved sheet actuated tripper mechanism for causing said sheet feeding and sheet separating mechanism to feed and separate the lowermost and superposed sheets held by the pile supporting means in coöperative 35 and properly timed relation to the gripping rolls and other parts of the press.

A still further object is the provision of 40 improved sheet feeding and sheet separating mechanism together with improved means for actuating the same with relation to the superposed pile or stack of sheets to be fed.

With the above mentioned and other ends 45 in view, the invention consists in the novel construction, arrangement, and combination 50 of parts, hereinafter described, illustrated in one of its embodiments in the accompanying drawings, and particularly pointed out in the appended claims.

Referring to the drawings forming a part 55 of this specification, Figure 1, is a side elevation of the improved machine as it appears attached to the front or feed end of the press.

Fig. 2, an enlarged top plan view of the

same, the pile supporting carriage, and sheet 55 separating carriage being slightly separated from the position shown in Fig. 1, of the drawings.

Fig. 3, an enlarged detailed side elevation of the sheet feeding and sheet separating 60 mechanism certain portions being omitted illustrating the manner in which the sheets are fed out and separated from the pile, the dotted lines illustrating the throw of the parts after the actuation of the sheet actuated tripper mechanism by the sheet of paper being fed.

Fig. 4, a detailed fragmentary view of the "comber" wheel actuating and adjusting mechanism.

Similar numerals of reference designate like parts throughout all the figures of the drawings.

The improved paper feeding machine comprises a suitable frame made up, in the 75 present instance, of guide members for the carriages hereinafter referred to as well as acting to support and form bearings for certain mechanism. The guide members 1, are connected by means of cross bars 1^a, and a 80 longitudinally extending median member 1^b, the latter being provided at its rear with a longitudinal slot 1^c. The side members 1, of the frame may form a part of the press or 85 may be suitably attached thereto as desired.

As a means of adapting and adjusting the pile supporting and sheet feeding and separating mechanism to the dimensions or form of the pile or stack of sheets to be fed, pile supporting and sheet feeding carriages 2, 90 and 3, respectively, are slidably mounted on the guide members 1, said carriages 2, and 3, in the present instance, being in the form of channelled slides oppositely arranged in pairs, the slides or supports 2, being connected by means of an upwardly extending pile support 2^a, the latter being provided with an adjustably mounted support or guide 2^b, said support or guide 2^b, being adapted to support and guide the front or delivery side of the pile or stack of sheets 2^c, to be fed by the machine, said guide or support 2^b, forming a sheet delivery slot 2^d, at its bottom for the delivery of the sheets from the pile as hereinafter explained. As 95 a means of raising or lowering the guide 2^b, whereby to regulate the size of the sheet delivery slot 2^b, to conform to varying thick-

nesses of sheets in the pile to be fed, the support 2^a, may be provided with adjusting screws 2^c, fitted in slots 2^f, and screwed into the guide 2^b, for operating in a well known 5 and understood manner.

The sheet feeding carriage 3, comprising the channeled guides, is provided with an oscillatory or rock shaft 4, carrying a pair of supporting arms 5, the latter terminating 10 at their free ends in bearing heads 5^a, carrying a driving shaft 6. The shaft 6, is provided, in the present instance, at one end with a pinion 6^a, meshing with the driving gear 7, communicating with suitable gearing 15 hereinafter described and adapted to transmit motion to the shaft 6, the latter being provided with sheet feeding members 8, consisting, in the present instance, of sheet delivery or "comber" wheels armed with sheet 20 engaging and feeding members 8^a.

As a means of enabling the sheet feeding or "comber" wheels 8, to feed or comb out the sheets of paper from the pile or stack in stages and particularly of separating the 25 second sheet 2^g, and superposed sheets in the pile, from the first sheet 2^h, while being finally fed out and engaged by the sheet gripping drop rolls as shown most clearly in Fig. 3, of the drawings, a sheet separating 30 device consisting, in the present instance, of a pivoted lever 9, terminating at its free end in an upwardly extending pointed sheet engaging portion 9^a, is mounted on a cross bar 10, said lever 9, or sheet engaging and separating 35 device and said "comber" wheels being adapted to be oscillated and to be alternately brought into and out of contact with the superposed sheets of paper in the pile by the mechanism hereinafter described in 40 the sheet feeding and separating operation so that the sheet engaging portion 9^a, will engage with the second sheet 2^g, to hold the latter while the first sheet 2^h, is finally fed out by the "comber" wheels 8, and the sheet 45 carrying and gripping rolls hereinafter described.

As a means of supporting and carrying the sheets from the pile and as fed therefrom by the sheet feeding and separating mechanism above referred to, suitable sheet carrying means are provided, in the present instance, in the form of front and rear rollers 11, and 12, respectively, mounted on shafts 11^a and 12^a, carried in suitable bearings of 50 the machine frame, said rolls 11, and 12, being provided with sheet carrying webs or tapes 13, extending beneath the pile of paper and from the sheet feeding and separating mechanism hereinbefore referred to 55 and to the sheet receiving or feeding portion of the press.

The front shaft 11^a, may be driven by means of a suitable gear 14, communicating with any suitable and convenient source of 60 power, and as a means of gripping and feed-

ing each sheet 2^h, as delivered, a pair of drop rolls 15, may be mounted upon a shaft 16, carried upon a pair of supporting arms 17, the latter being adapted to be reciprocated by means of a rock shaft 18, mounted in the 70 side members 1, and reciprocated by means of a crank arm 18^c, connected to a rod 19, leading to some suitable source of power on the press or machine.

As a means of driving the shaft 6, and 75 the sheet feeding wheels 8, carried thereby, one of the slides 3, in the present instance, is provided with depending bearings 3^a, adapted to receive and contain a driving shaft 20, carrying a pair of spirals 21, meshing with spiral-gears 22, carried on stub shafts 23. The shafts 23, are provided with ratchet wheels 24, and one of the shafts 23, is provided with a gear 7, meshing with the pinion 6^a, on the driving shaft 6, carrying 80 the sheet feeding wheels 8, whereby the latter are continuously driven, and as a means of oscillating the sheet feeding wheels 8, and sheet separating lever 9, whereby to alternately and successively bring such devices into 85 and out of contact with the superposed sheets in the pile, the rock shaft 4, is provided at one end with an arm 26, said arm 26, carrying a roller 27, adapted to ride upon and receive motion from a reciprocating slide 28, 90 said slide 28, operating in guide brackets 29, and as a means of causing said slide 28, to reciprocate in the guides 29, as timed by the sheet actuated tripper mechanism herein- 95 after described, the slide 28, is provided with an oscillatory detent member 30, adapted to rock on a pivot screw 31, and to be alternately engaged and to play between the ratchet wheels 24. The slide 28, is provided with a beveled or inclined portion 28^a, adapt- 100 ed to ride under the roller 27, and elevate the arm 26, when shifted to the dotted line position shown in Fig. 3, of the drawings thereby rocking the shaft 4, and causing the feeding wheels 8, to be elevated and the sheet 105 separating device 9, to be dropped to the dotted line position shown in Fig. 3, of the drawings, the lever 9, being operated and controlled by the coaction between the short arm 9^b, and the arm 4^a, on the rock shaft 4, 110 an adjusting screw 4^b, in the latter operating against the arm 9^b, controlling the throw or oscillation of the sheet engaging free end of the lever or sheet separating member 9, in an 115 obvious manner.

The sheet actuated tripper mechanism for causing the sheet feeding and separating mechanism to alternately and successively feed and release the second sheet, after the first sheet has been fed out sufficiently to release the tripper mechanism, comprises an upwardly extending tripper lever 32, having its free end normally disposed within the path of the sheet being fed and mounted on a rock shaft 33, the latter being mounted in 125 130

suitable bearings on the main frame and provided at one side of the latter with a cam head 33^a, normally in engagement with and holding in an elevated position a bearing head 34^a, of a vertically movable bar 34, the latter being slidably mounted in a guide bracket 35, and connected at its upper end to a short crank 36, carried on a rock shaft 37. The shaft 37, is mounted in a bracket 38, on 10 the main frame and a plurality of brackets 3^b, of the slide or carriage 3.

The rock shaft 37, is provided with a longitudinal groove or key-way 37^a, to receive a key or spline for securing a second 15 short lever 39, extending outwardly and carrying a bar 40, vertically movable at its lower end in a guide lug 29^a, of the bracket 29, the lower end of said bar 40, normally resting upon the detent member 30, at one 20 side of the pivot 31, and normally holding the adjacent side of said detent member downwardly against the resistance of a spring 41, and in engagement with the adjacent ratchet wheel 24. It will be apparent 25 that when the sheet being fed out strikes the tripper lever 32, when in its normal position as shown in Fig. 1, and moves said lever to the dotted line position shown in such figure or the full line position shown in Fig. 3, the 30 cam head 33^a, will be shifted and the bar 40, will be elevated by the action of a spring 41, under the oscillatory detent 30, whereby the opposite end of the detent will drop down to the dotted line position shown in Fig. 3, of 35 the drawings and the adjacent ratchet wheel will return the detent to its original position shown in full lines in the drawings to be re-engaged by the opposite ratchet so that the slide 28, will be intermittently reciprocated 40 between the two ratchets 24, and controlled by the actuation of the sheet actuated tripper 32. The projection 14^a, on the gear 14, by engagement with the cam 33^a, will return the lever 32, and other connected parts to 45 their original position.

As a means of simultaneously moving the slides or carriages 2, and 3, toward and from each other for adjusting the mechanism carried thereby to stacks or piles of paper of 50 varying dimensions, the carriage 2, is provided with a rock shaft 42, extending through slots 1^d, in the side members 1, and provided at its ends with cross arms 43, connected to link members 44, the outer ends of 55 the latter being connected to stubs 45, and 46, on the adjacent side members and the slides 3, of the carriage, respectively, so that upon the actuation of the rock shaft 42, through the medium of the hand wheel 47, 60 the slides or carriages 2, and 3, with their various attachments may be simultaneously actuated, the key-way 37^a, on the shaft 37, permitting the lever 39, to slide with the movement of the carriage 3, and the key-way 65 20^a, on the driving shaft 20, permitting the

spiral 21, between the depending bearing lugs 23^a, to slide also with the sliding or adjusting movements imparted to the carriage 3.

As a means of adjustably supporting the 70 arms 5, on the rock shaft 4, whereby the driving shaft 6, and the sheet feeding or comber wheels 8, may be adjusted to regulate the throw of the latter with respect to the paper being fed from the pile of sheets, and 75 also as a means of independently adjusting each end of the shaft 4, for regulating the feeding of the sheets at each side, each arm 5, is provided at its base with a laterally extending arm 5^b, resting against a pair of adjusting bolts 48, carried in rearwardly extending bearing lugs 49, in the present instance, being formed as a part of a clamp 49^a, secured at one end of the rock shaft 4, and at the other made a part of the arm 26, 80 as shown most clearly in Fig. 4, of the drawings.

If desired, the bed of the frame may be provided with a pair of angle iron paper guide members 1^e, extending longitudinally 90 of the frame and adapted to support and form guides for the lower sheets in the pile as well as while such sheets are being fed therefrom by the mechanism hereinbefore referred to.

From the foregoing description, taken in connection with the accompanying drawings, the operation and advantages of my invention will be readily understood.

Having thus described one of the embodiments of my invention, what I claim and desire to secure by Letters Patent, is,—

1. A paper feeding machine, comprising a frame including guide members, pile supporting and sheet feeding mechanism slidably and adjustably mounted on said guide members, sheet carrying webs on said frame below said pile supporting mechanism, means for driving said sheet feeding mechanism, and sheet actuated tripper mechanism for 105 operating said sheet feeding mechanism in coöperative relation with the movements of the sheets being fed.

2. A paper feeding machine, comprising a frame, pile supporting and sheet feeding 115 and separating mechanism mounted thereon, sheet carrying means below said pile supporting mechanism and extending in front of said sheet feeding and separating mechanism, oscillatory sheet gripping drop rolls 120 in coöperative relation to said sheet carrying means, and sheet actuated tripper mechanism for operating said sheet feeding and separating mechanism in coöperative relation with the movement of the sheet being fed. 125

3. In a paper feeding machine, a carriage provided with an oscillatory driving shaft carrying "comber" wheels, an oscillatory sheet separating device in coöperative relation to the latter, means for continuously 130

driving said shaft and "comber" wheels, means for oscillating the latter and said sheet separating device in opposite directions to alternately contact with the sheets 5 to be fed, and sheet actuated mechanism controlling said last mentioned means through the feed movements of the first sheet being fed.

4. A paper feeding machine, comprising 10 a frame, pile supporting means, sheet feeding and separating mechanism below the latter, sheet carrying means in coöperative relation to said mechanism, means for driving said sheet feeding mechanism, means for 15 oscillating said sheet feeding and said sheet separating mechanism in coöperative relation to each other, and sheet actuated tripper mechanism for operating and controlling said sheet feeding and separating mechanism in coöperative relation to the movements of the sheets being fed.

5. In a paper feeding machine, a sheet feeding and separating mechanism comprising a driving shaft provided with "comber" 50 wheels, a rock shaft provided with arms carrying said driving shaft, an oscillatory sheet engaging and separating member, means on said rock shaft for operating said sheet engaging and separating member in coöperative relation to said "comber" 55 wheels whereby the second sheet is held while the first sheet is being moved by said "comber" wheels, means for driving the latter, and means for rocking said rock shaft from said driving means.

6. A paper feeding machine, comprising a frame provided with guide members, pile supporting means and sheet feeding mechanism 40 slidably mounted on said guide members, oscillatory sheet gripping drop rolls, sheet carrying means between the latter and said sheet feeding and separating mechanism, means for simultaneously adjusting said pile supporting means and said sheet 45 feeding and separating mechanism, and sheet actuated tripper mechanism for causing said sheet feeding and separating mechanism to successively feed and separate the sheets from said pile supporting means.

50 7. In a paper feeding machine, the combination with a frame including guide members, and pile supporting and sheet feeding carriages slidably mounted on the latter; of a rock shaft carried by said pile supporting carriage and provided with oppositely extending link members, one of said link members being connected to said frame and the other to said sheet feeding carriage whereby said carriages may be simultaneously moved toward and from each other on said guide members and the movement imparted to said sheet feeding carriage will be twice that imparted to said pile supporting carriage.

65 8. In a paper feeding machine, a frame,

pile supporting and sheet feeding mechanism adjustably mounted thereon, sheet carrying means in coöperative relation to said sheet feeding mechanism, sheet separating mechanism in coöperative relation to said sheet feeding mechanism, means for driving said sheet feeding mechanism, means for reciprocating said sheet feeding mechanism while being driven and operating said sheet separating mechanism in coöperative relation thereto, and means for controlling said sheet feeding and sheet separating mechanism by the outlet passage of the sheet being fed.

9. A paper feeding machine, comprising a frame provided with guide members, pile supporting and sheet feeding and separating mechanism slidably mounted on said guide members, means for simultaneously moving and adjusting said pile supporting 85 and said sheet feeding and separating mechanism toward and from each other, sheet carrying means in coöperative relation to said pile supporting and sheet separating mechanism, oscillatory sheet gripping drop 90 rolls in coöperative relation to the latter, means for driving said sheet feeding mechanism, means for operating said sheet separating mechanism and reciprocating said sheet feeding mechanism in coöperative relation to each other, and sheet actuated tripper mechanism controlling the operation of said sheet feeding and sheet separating mechanisms in coöperative relation 95 to the movement of the sheet being fed. 100

10. In a paper feeding machine, the combination with a frame including guide members, and a driving shaft provided with splined gears; of pile supporting and sheet feeding carriages slidably mounted on said guide members, said sheet feeding carriage being also slidably connected on said driving shaft and provided with sheet feeding mechanism driven from said gears, and a rock shaft carried by said pile supporting 105 carriage and provided with a cross arm carrying link members being connected to said frame and the other to said sheet feeding carriage whereby said carriages may be simultaneously moved from and 110 toward each other to conform to piles of varying dimensions.

11. In a paper feeding machine, a sheet feeding carriage provided with an oscillatory shaft carrying supporting arms, a driving shaft carried by said arms and provided with sheet feeding wheels, driving mechanism on said carriage operatively connected to said driving shaft and wheels, ratchet and detent mechanism on said carriage 120 driven by said driving mechanism and adapted to oscillate said rock shaft and thereby reciprocate said driving shaft and sheet feeding wheels while being driven by said driving mechanism, and sheet separat- 125 130

ing mechanism on said carriage reciprocated by said rock shaft in coöperative relation to said sheet feeding wheels.

12. In a paper feeding machine, a frame, 5 pile supporting and sheet feeding mechanism mounted thereon, a rock shaft provided at one side with a driving shaft carrying "comber" wheels beneath said pile supporting mechanism, means for driving said 10 driving shaft and "comber" wheels, sheet separating mechanism beneath said pile supporting mechanism and in coöperative relation to said "comber" wheels, means connecting said sheet separating mechanism 15 with said rock shaft whereby said sheet separating mechanism will be oscillated in an opposite direction to said driving shaft and "comber" wheels when said rock shaft is oscillated, and means for oscillating said 20 rock shaft through said driving mechanism.

13. A sheet feeding machine comprising means for supporting a stack of sheets, a vertically movable bearing, a combing wheel journaled therein and adapted to engage the 25 bottom sheet, a finger arranged in the path of an advancing sheet, and means controlled by said finger, for raising and lowering said bearing.

14. A sheet feeding machine comprising 30 means for supporting a stack of sheets, a vertically movable bearing, a combing wheel journaled therein and adapted to engage the bottom sheet, a finger arranged in the path of an advancing sheet, a reciprocable lifter 35 adapted to operatively engage said bearing, and means controlled by the finger for actuating said lifter.

15. A sheet feeding machine comprising 40 means for supporting a stack of sheets, a vertically movable shaft, a combing wheel mounted thereon, a lifter adapted to raise or lower the shaft, a rock shaft, a finger mounted thereon, means controlled by the finger for actuating the lifter, and a plurality of feed belts, extending from the 45 combing wheel toward the rock shaft.

16. A sheet feeding machine comprising 50 means for supporting a stack of sheets, a vertically movable shaft, a combing wheel mounted thereon, a gripper actuated by the combing wheel, a lifter adapted to raise and lower the shaft, a finger in the path of the

advancing sheet, means controlled by said finger for actuating the lifter, feed belts extending from the combing wheel toward 55 the finger, and a pair of feed rollers arranged in proximity to the finger.

17. A sheet feeding machine, comprising means for supporting a stack of sheets, a vertically displaceable combing roller adapted to engage the bottom sheet, an oppositely movable gripper adapted to engage the heels of the adjoining sheets, a member in the path of an advancing sheet, and means operable by said member for mechanically raising the 60 combing wheel and depressing the gripper, or for depressing the combing wheel and raising the gripper.

18. A sheet feeding machine, comprising means for supporting a stack of sheets, 70 means for advancing the bottom sheet, means for restraining the adjoining sheets, and means controlled by an advancing sheet, for simultaneously moving the sheet-advancing means and the sheet-restraining means in 75 opposite directions.

19. A sheet feeding machine comprising a vertically movable bearing, a combing wheel journaled therein, a slide adapted to raise and lower the bearing, a pair of oppositely 80 rotatable members, and sheet controlled means for alternately coupling said slide to said members.

20. A sheet feeding machine comprising a vertically movable bearing, a combing wheel 85 journaled therein, a slide adapted to raise and lower the bearing, a pair of opposed ratchet wheels, and sheet controlled means for alternately coupling the slide to said wheels.

21. A sheet feeding machine comprising a vertically movable bearing, a combing wheel journaled therein, a tapering slide for moving the bearing, a double pawl pivoted to the slide, a pair of opposed ratchet wheels, 95 and sheet controlled means for throwing the pawl into alternate engagement with said wheels.

In testimony whereof I have affixed my signature in the presence of two witnesses.

RICHARD J. NETZEL.
